(57) **CLAIM**

The ornamental design for a vanity mirror with speaker base, as shown and described.

DESCRIPTION

FIG. 1 is a top perspective view of the front of the vanity mirror with speaker base of the present design.

FIG. 2 is a bottom perspective view of the rear of the vanity mirror with speaker base of FIG. 1.

FIG. 3 is a front elevation view of the vanity mirror with speaker base of FIG. 1.

FIG. 4 is a rear elevation view of the vanity mirror with speaker base of FIG. 1.

FIG. 5 is a side elevation view of the right side of the vanity mirror with speaker base of FIG. 1.

FIG. 6 is a side elevation view of the left side of the vanity mirror with speaker base of FIG. 1.

FIG. 7 is a top plan view of the vanity mirror with speaker base of FIG. 1; and,

FIG. 8 is a bottom plan view of the vanity mirror with speaker base of FIG. 1.

In the drawings, the broken lines depict portions of the vanity mirror with speaker base that form no part of the claimed design.
